UNITED STATES PATENT OFFICE

2,205,459

CIRCULAR RACING TOY

Joseph S. Bardegia, Detroit, Mich.

Application October 14, 1938, Serial No. 235,074

1 Claim. (Cl. 104—147)

The present invention relates to new and useful improvements in circular racing toys or amusement devices of the type including an annular raceway over which a plurality of cars or other objects are adapted to travel and has for one of its important objects to provide, in a manner as hereinafter set forth, novel means for driving said cars or other objects in a manner to cause them to travel at different speeds at different points, to pass one another, etc., thus closely simulating a real race and providing considerable amusement and entertainment.

Another very important object of the invention is to provide a racing toy of the aforementioned character embodying driving means for the cars or other objects of such a construction and arrangement that any of the cars may win the race. In other words, the propelling of the cars is what may be considered chance controlled.

Other objects of the invention are to provide a racing toy of the character described which will be comparatively simple in construction, strong, durable, attractive in appearance, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of a racing toy constructed in accordance with the present invention.

Figure 2 is an elevational view thereof.

Figure 3 is a top plan view of the driving disc, the motor shaft being shown in section.

Figure 4 is a view in vertical longitudinal section through one of the cars.

Figure 5 is a cross sectional view through one of the cars, taken substantially on the line 5—5 of Fig. 4.

Figure 6 is a vertical sectional view through a portion of the device, taken substantially on the line 6—6 of Fig. 1.

Figure 7 is a fragmentary sectional view, taken substantially on the line 7—7 of Fig. 1.

Referring now to the drawings in detail, it will be seen that the embodiment of the invention which has been illustrated comprises a circular platform 1 of suitable sheet metal. On its periphery, the circular platform 1 is provided with an integral, downturned supporting flange or

skirt 2 which rests on a base 3, also of suitable metal.

The marginal portion of the circular platform 1 is depressed and otherwise formed to provide an inclined or banked circular raceway which is designated generally by the reference numeral 4. Guides 5 which are integral with the metallic platform 1 divide the raceway 4 into a plurality of circular, concentric tracks 6. Each track 6 has formed therein a plurality of substantially segmental slots 7 the ends of which are spaced from each other, as illustrated to advantage in Fig. 1 of the drawings. The slots 7 are preferably formed by piercing the metal, thus providing depending reinforcing lips or flanges 8 (see Fig. 6). 15

In the embodiment illustrated, cars designated generally by the reference numeral 9 are adapted to travel around the tracks 6, being restricted to said tracks by the guides 5. One car is provided for each track. Referring now to Figs. 4 and 5 20 of the drawings, it will be observed that each car 9 includes a suitable body 10 mounted on axles 11. The end portions of the axles 11 carry wheels 12. Loosely mounted for swinging movement on each axle 11 is a pawl 13. The pawls 13 25 are operable in the slots 7 of the tracks 6.

Mounted on substantially the central portion of the platform 1 is a spring motor 14. An up-standing winding key 15 is provided for the motor 14. The motor 14 is enclosed in a housing 16 30 of suitable metal which, as shown to advantage in Figs. 1 and 2 of the drawings, is formed to simulate a grandstand. It will be noted that the shank of the motor winding key 15 passes rotatably through the top of the motor housing 16. 35

The shaft 17 of the motor 14 extends downwardly through the platform 1 and has rigidly secured on its lower end a driving disc 18 of suitable metal. Rollers 19 are provided beneath the platform 1 for preventing excessive 40 wobbling of the driving disc 18. The driving disc 18 comprises an inclined or banked marginal portion 20 corresponding substantially to the banked raceway 4 of the platform 1. Rising from the marginal portion 20 of the driving disc 18 are 45 what may be referred to as teeth or abutments 21. The teeth 21 are arranged to provide spaced circular series, each series being adapted to travel beneath the slots 7 in one of the circular tracks 6. Thus, the teeth 21 are engageable 50 with the pawls 13 for propelling the cars 9.

It is thought that the operation of the device will be readily apparent from a consideration of the foregoing. The cars 9 are placed at a starting point on their respective circular tracks 6 55

with the pawls 13 thereof hanging through the slots 7 at that particular point and resting on the disc 18, or possibly on one of the teeth 21. The disc 18 is then actuated by the motor 14. 5 When the disk 18 rotates the teeth 21 engage the pawls 13 and push the cars 9 around the tracks 6. The same number of teeth 21 are provided for each of the tracks 6. As shown to advantage in Fig. 3 of the drawings, the teeth 21 10 of each circular series are arranged in differently spaced groups or sections at different points. Also, the spacing of the teeth 21 at one point or section for one of the tracks 6 is preferably different from the spacing of the adjacent teeth. Briefly, the arrangement of the teeth is such 15 that the cars 9 will be caused to travel at different speeds at different points on their respective tracks and said cars will also be caused to pass and perhaps repass one another. When 20 the pawls 13 hit the forward ends of the slots 7 and drag over the connecting portions 22 of the tracks 6 between said slots, said pawls are, of course, disengaged from the teeth 21. After passing over the connecting portions 22 the pawls 25 13 drop into the next slot 7 to be again picked up by one of the teeth 21. Thus, the cars 9 are momentarily disconnected from or freed of the driving disc 18 as they travel around the tracks 6. Of course, the frequency of these disconnections is dependent on the number and length of 30 the slots 7. Each time a disconnection takes place the particular car involved loses ground or drops back relative to the driving disc 18 while the pawls 13 are again picked up by the next

following teeth. Thus, the uncertainty of the eventual winner of the race is further increased. As best seen in Figure 7, the connecting portions 22 between the circumferential slots 7 are grooved in a manner to provide guides for the 5 pawls 13 as said pawls travel thereover between said slots.

It is believed that the many advantages of a racing toy constructed in accordance with the present invention will be readily understood and 10 although a preferred embodiment of the device is as illustrated and described, it is to be understood that changes in the details of construction and in the combination and arrangement of parts may be resorted to which will fall within the 15 scope of the invention as claimed.

What is claimed is:

A racing toy comprising a platform including a plurality of circular tracks, each track having circumferentially spaced slots therein, a disc 20 rotatably mounted beneath the platform, means for actuating the disc, spaced teeth on the disc beneath the slots, wheel supported members operable on the tracks, and pawls pivotally mounted on said members and operable in the slots for 25 releasably connecting the members to the disc for actuation thereby, said pawls being engageable with the platform at the ends of the slots for periodically disconnecting the members from the disc, the platform having circumferential 30 grooves therein connecting the spaced slots for guiding the pawls therebetween.

JOSEPH S. BARDEGA.
